RAZOR SHARPENING DEVICE

Ralph W. McMullen, Detroit, Mich., assignor of
one-half to Herbert H. Rice, Detroit, Mich.

Application June 17, 1932, Serial No. 617,903

7 Claims. (Cl. 51—158)

This invention relates generally to razor blade sharpening equipment and refers more particularly to improvements in devices for conditioning razor blades.

6 The invention has as one of its primary objects to provide sharpening equipment for razor blades distinguished by its simplicity in construction and operation which not only enhances its value both mechanically and commercially, but provides a compact design capable of being expediently manipulated to efficiently sharpen the cutting edge portions of razor blades.

Much of the commercial value and acceptability of the present invention is attributed to 15 the particular manner in which the sharpening device functions to hone the cutting edge portions of the blade. In accordance with this invention, continuous contact of the cutting edge portions of the blade with the cooperating abrasive member during the sharpening operation is insured 20 without any special attention on the part of the operator, and, moreover, provision is made for automatically supporting the blade at the proper cutting angle with respect to the aforesaid 25 abrasive member.

Another advantageous feature of the present invention which contributes materially to the efficiency of operation of the device consists in 30 the provision of a design capable of sharpening the cutting edge portions of razor blades by moving the latter relative to the abrasive member in directions toward the aforesaid cutting edge portions thereof.

Another object of the present invention which 35 provides for expediting the sharpening operation consists in the provision of a device having a blade holder fashioned to alternately move opposed cutting edge portions of a blade in contact with an abrasive member upon movement 40 of the device in opposite directions relative to the said member.

Still another object of this invention consists 45 in the provision of means associated with the device and movable into engagement with the blade holder for supporting the blade in the latter in a predetermined fixed position suitable for stropping purposes as distinguished from honing.

A further advantageous feature consists in 50 the provision of means associated with the device and operable in the fixed or stropping position of the blade holder to form a guard for one cutting edge of the blade during stropping of the other edge thereof.

A still further object of the present invention 55 consists in the provision of a relatively simple

blade holder capable of being readily manipulated to provide for expediently assembling a blade therewith and removing the same therefrom.

In addition to the foregoing, the present invention consists in the provision of means for rockably supporting the abrasive member during the sharpening operation so as to insure a continuous contact between the cutting edge of the blade and upper surface of the abrasive member 65 without depending upon the skill of the operator.

A further advantages feature of this invention resides in the provision of a case or container for the sharpening device and abrasive member having means associated therewith for rockably 70 supporting the latter member about its major axis for the purpose set forth in the preceding paragraph.

The foregoing as well as other objects will be 75 made more apparent as this description proceeds, especially when considered in connection with the accompanying drawings, wherein:

Figure 1 is a perspective view showing a sharpening device constructed in accordance with this invention in association with an abrasive member 80 rockably supported upon a part of the container for the latter elements;

Figure 2 is a longitudinal sectional view through the sharpening device shown in Figure 1;

Figure 3 is a fragmentary perspective view showing the sharpening device in operative relationship to an abrasive member;

Figure 4 is a sectional view taken substantially 90 on the line 4—4 of Figure 3;

Figure 5 is a perspective view of the sharpening device showing the manner in which the blade holder is held in a fixed predetermined position relative to the frame preparatory to the stropping operation;

Figure 6 is a view similar to Figure 3 showing 95 a slightly modified form of construction;

Figure 7 is a longitudinal sectional view through the sharpening device shown in Figure 6;

Figure 8 is a view similar to Figure 6 showing 100 the sharpening device in a different position relative to the abrasive member; and

Figure 9 is a sectional view taken substantially 105 on the line 9—9 of Figure 8.

Although both embodiments of the invention 110 about to be described are readily adaptable for use in sharpening various types of razor blades, nevertheless, for the purpose of illustration, I have shown the following constructions as utilized for sharpening blades having double or

opposed cutting edges. In general, both devices about to be described are provided with blade holders rotatably mounted upon a frame and having beads or cam portions projecting laterally from opposite faces thereof fashioned to not only support the cutting edges of the blade at the proper angle with respect to the abrasive member, but to also rock the blade holder relative to the frame for alternately engaging opposite cutting edge portions of the blade with the abrasive member upon movement of the device in opposite directions with respect to the abrasive member. It will further be apparent that in each embodiment of the invention sharpening of the opposed cutting edges of the blade is effected by moving the blade through the medium of the frame in a direction toward the edge being sharpened. This arrangement insures efficient and expedient sharpening of the cutting edges of the blade.

Referring now more in detail to the specific embodiment of the invention illustrated in Figures 1 to 5, inclusive, it will be noted that the sharpening device 10 comprises a blade holder 11 mounted for rotation about its major axis upon a frame 12. The frame 12 is substantially rectangular in shape having an upper bar 13 and a lower bar 14 integrally connected at its end to the upper bar by means of the transverse end portions 15. The lower bar 14 of the frame is cut away adjacent one end of the latter providing spaced axially aligned pintels 16 engageable within counterbored portions 17 formed in opposite ends of the holder coincident with the major axis of the latter. The counterbores 17 are of such length as to provide for the desired restricted reciprocable movement of the blade holder in the direction of its major axis during the sharpening operation and also permits the holder to be readily removed from the frame.

The blade holder 11 comprises the rotatably mounted section 18 and a clamping section 19 pivotally connected as at 20 to the section 18 adjacent one end portion thereof. The pivotally mounted section 19 of the blade holder is provided with an offset finger engaging portion 21 adjacent to the pivotal connection aforesaid and extending beyond the same as shown in Figure 2. The arrangement is such that by merely depressing the finger engaging portion 21, the remaining or blade clamping portions of the section 19 are moved about the pivot 20 away from the section 18 so as to provide for either removing or placing a blade between the aforesaid sections. The blade clamping portion of the section 19 is normally yieldably urged into clamping relation with respect to the section 18 by means of a coil spring 22 having one end seated within a recess 23 formed in the section 18 and having the other end abutting the finger engaging portion 21 of the section 19.

The blade clamping portion of the section 19 is provided with a series of openings 24 therethrough spaced along the major axis of the holder and fashioned to receive suitable projections 25 extending laterally from the section 18 toward the section 19. The projections 25 on the section 18 are accurately spaced in dependence upon the usual openings formed in razor blades and serve to accurately position the latter within the holder. Furthermore, the projections 25 actually prevent twisting or shifting of the blade relative to the holder when in operative position with respect thereto.

In order to provide for alternately engaging

the opposite cutting edge portions of the blade with the abrasive members during movement of the sharpening device in opposite directions, each of the sections aforesaid of the blade holder is formed with arcuate beads or cam portions 26 and 27 extending along the major axes of the sections. As shown particularly in Figure 4, the cam portions are arcuate in cross section so as to provide for the desired rocking movement of the holder, and, furthermore, are so fashioned that the portions thereof adapted to contact with the abrasive member during the sharpening operation are arranged in a common plane with the beveled surface of the cutting edge being honed. The above arrangement is clearly shown in Figure 4 and insures complete contact of the beveled surfaces transversely of the blade with the abrasive member.

With the device as thus far described, a blade to be sharpened is assembled with the holder by manipulation of the section 19 thereof in the manner hereinbefore stated and the device is positioned relative to an abrasive member 30 as shown in Figure 1 with the arcuate bead 26 on the section 18 in contact with the upper surface of the abrasive member. The device is then moved in one direction relative to the abrasive member causing the bead 26 to rock the holder 11 in a direction to engage the lower beveled cutting edge extending in the direction of movement of the device with the upper surface of the abrasive member. After the device has been moved to the desired extent in the above mentioned direction, the same is moved in the opposite direction causing the arcuate bead 26 to rock the holder in a direction to engage the lower bevel of the opposite cutting edge with the upper surface of the abrasive member. Upon completion of the honing operation of the lower beveled surfaces of the cutting blade, the holder is merely inverted so as to position the upper beveled surfaces of the cutting edges adjacent the abrasive member. The inversion of the holder relative to the frame is permitted owing to the rotative mounting of the holder with the frame and due to the fact that the upper bar 13 of the frame is spaced a sufficient distance laterally from the lower bar as to provide ample clearance for the passage of the blade. In the inverted position of the holder, the bead 27 on the clamping section 19 of the holder is in engagement with the top surface of the abrasive member, and a duplication of the above operations serves to completely sharpen the cutting edges of the blade. Owing to the predetermined relationship existing between the contacting portions of the arcuate beads aforesaid and the beveled surfaces of the cutting edge portions of the blade, continuous contact of the latter surfaces with the abrasive member transversely of the blade is insured.

As previously stated, it is one of the important features of this invention to provide means for stropping the cutting edges of the blade subsequent to the honing operation, and this is accomplished herein without removing the blade from the holder on the sharpening device. In general, means is provided upon the frame of the device for engaging the blade holder to maintain the same in the position shown in Figure 5 wherein the top bar 13 of the frame forms a guard for the cutting edge of the blade opposite the edge being stropped. In detail, a suitable latch member 31 is slidably mounted upon the frame beyond the blade holder and is fashioned

for engagement within a slot 32 formed in the adjacent end of the holder. The slot 32 extends transversely of the holder in a common plane with the blade supported in the latter so that engagement of the latch member 31 within the slot 32 positions the blade in the manner shown in Figure 5. When the blade is in this latter position, it will be apparent that one edge of the same may be readily stropped while the other edge is protected by the upper bar of the frame.

When not in use, the sharpening device and abrasive member may be compactly arranged within a suitable case or container having a bottom section designated herein by the reference character 33. As shown, the case is provided with a compartment 34 for the sharpening device and with a juxtaposed compartment 35 for the abrasive member 30. The latter compartment is provided with a bottom wall 36 substantially V-shaped in cross section so as to support the abrasive member in such a manner as to permit rocking movement of the latter about its major axis during the sharpening operation. The arrangement is such that the upper surface of the abrasive member automatically adjusts itself with respect to the cutting edges of the blade so as to insure continuous engagement of the cutting edges of the blade with the abrasive member. Thus, it will be observed that the abrasive member need not be removed from its container during the sharpening operation, and upon completion of the latter function, the sharpening device may also be inserted within the compartment 34 in the container whereupon a suitable cover (not shown) may be engaged with the container.

Referring now to the modified form of the construction shown in Figures 6 to 9, inclusive, it will be noted that the blade holder 40 illustrated in the several views is basically similar to the blade holder 11 hereinbefore described with the exception that the holder 40 is provided with an enlargement 41 eccentrically arranged with respect to the major axis of the holder upon the side of the latter axis opposite the finger engaging portion 42 of the holder so as to counterbalance the weight of the latter portion. The operation of the holder to provide for expediently assembling the blade with and removing the same from the holder is substantially the same as defined in connection with the first described form of the invention. The cooperating engaging parts of the holder 40 are also provided with arcuate beads 43 identical in construction to the beads formed on the holder 11 for accomplishing the same results as the latter. In the present embodiment of the invention, however, the blade holder is moved relative to the abrasive member by means of a handle 44 swivelly connected to the upper bar of the frame as at 45. As will be observed from Figure 7, the handle is located at substantially the center of the sharpening device which, together with the swivel connection hereinbefore referred to, provides for the application of even pressure on the cutting edge of the blade during the sharpening operation without any special attention on the part of the user.

Although in a construction having a swivelly connected handle of the type set forth above, it is not essential to provide for rocking movement of the abrasive member to insure contact of the cutting edge of the blade throughout its length with the abrasive member, nevertheless, I have incorporated as a part of the latter modification an abrasive member having a bead 50 formed on

the lower surface of the abrasive member in such a manner as to provide for rocking movement of the latter about its major axis during the sharpening operation. The bead 50 may either be formed integral with the abrasive member or may be independently fashioned and united to the abrasive member in any suitable manner. In this connection, it is to be noted that an abrasive member of this latter character may be also employed in association with the first described form of the invention in which event the specially constructed container hereinbefore referred to may be eliminated.

While only two embodiments of the invention have been shown and described herein somewhat in detail, nevertheless, it is to be understood that various other modifications may be resorted to for effecting the desired results set forth herein, and, accordingly, reservation is made to make such changes as may come within the purview of the accompanying claims.

What I claim as my invention is:

1. In a razor blade sharpening device, a frame member, a handle for said frame member loosely connected to the same, a blade holder rotatably mounted upon said frame member, and means on said holder engageable with an abrasive member for rocking said holder to engage the cutting edge of a blade in the holder with the aforesaid abrasive member upon movement of the frame relative to the latter member in a direction toward the cutting edge of the blade.

2. In a razor blade sharpening device, a frame member, a handle for said frame member swivelly connected to the same, a blade holder mounted upon the frame member for rotation relative thereto and having means for clamping a double-edged blade thereto with the cutting edges projecting beyond opposite sides thereof, and means on the holder engageable with an abrasive member for actuating the holder to alternately move the opposite cutting edges of the blade in contact with an abrasive member upon movement of the frame in opposite directions relative to the abrasive member.

3. In a razor blade sharpening device, a frame member, a handle for said frame member swivelly secured to the same, a blade holder mounted upon the frame member for rocking movement about its major axis and having means for securing a double-edged blade thereto with the cutting edges of the blade extending beyond opposite sides thereof in substantial parallel relation with the major axis of the same, and means upon the holder engageable with an abrasive member for rocking the holder about its major axis to alternately engage the cutting edge portions of the blade with the abrasive member upon movement of the frame in opposite directions relative to said latter member.

4. In a razor blade sharpening device, a frame member, a handle for said frame member swivelly secured to the same, a blade holder mounted upon said frame member for rocking movement about its major axis and having means associated therewith for clamping a double-edged blade thereto with the cutting edges of the blade extending substantially parallel to the major axis of the holder laterally beyond opposite sides thereof, and a transversely curved bead integral with and extending the length of said holder coincident with the major axis thereof and engageable with an abrasive member for rocking the holder to alternately engage the opposite cutting edges of the blade with the abrasive member upon

movement of the frame in opposite directions relative to the latter member, said bead fashioned to provide for effecting continuous engagement of the beveled cutting surfaces of the blade with the abrasive member transversely of the blade.

5. In a razor blade sharpening device, a frame member, a handle for said frame member swivelly secured to the same, a blade holder mounted upon the frame for rotation about its major axis relative to the frame and having means for removably clamping a double-edged blade thereto with the cutting edges of the blade extending substantially parallel to the major axis of the holder and projecting laterally beyond opposite edges thereof, and means on opposite sides of the holder formed integral and extending the full length thereof for selective engagement with an abrasive member for rocking the holder about its axis to alternately engage the cutting edges of the blade with the abrasive member upon movement of the frame in opposite directions relative to the latter member.
6. In a razor blade sharpening device, a frame member, a handle for said frame member swivelly secured to the same, a blade holder mounted for rotation about its major axis upon the frame member and having means for removably clamping a double-edged blade thereto with the cutting edges of the blade substantially parallel to the major axis of the holder and extending lat-

erally beyond opposite edges of the latter, and transversely curved beads formed on opposite sides of and integral with the holder coincident with the major axis thereof and selectively engageable with an abrasive member for rocking the holder to alternately engage opposite cutting edges of the blade with the abrasive member upon movement of the frame in opposite directions relative to the latter member, both of said beads fashioned to extend the full length of the blade holder to provide for continuous engagement of the beveled surfaces of the blade with the abrasive member transversely of the blade.

7. In a razor blade sharpening device, a frame member, a blade holder mounted for rocking movement upon the frame member and having means associated therewith for clamping a double-edged blade thereto with the cutting edges of the blade projecting laterally beyond opposite edges of the holder, means upon the holder and engageable with an abrasive member for rocking the holder to alternately engage the opposite cutting edges of the blade with the abrasive member upon movement of the frame member in opposite directions relative to the abrasive member, and means slidably mounted upon the frame and engageable with the holder for securing the same against movement in a position to permit stropping one cutting edge of the blade.
